Primary Examiner — Barbara Fox*Assistant Examiner* — Kristin E Reed(74) *Attorney, Agent, or Firm* — Sughrue Mion, PLLC(57) **CLAIM**

The ornamental design for an electronic device, as shown and described.

DESCRIPTION

FIG. 1 is a top rear perspective view of an electronic device showing our new design;

FIG. 2 is a top view thereof;

FIG. 3 is a bottom view thereof;

FIG. 4 is a front view thereof;

FIG. 5 is a rear view thereof;

FIG. 6 is a left view thereof; and,

FIG. 7 is a right view thereof.

The features shown in dash-dot broken lines depict portions of the electronic device that form no part of the claimed design.

The dash-dot broken lines define the bounds of the claimed design and form no part thereof.

1 Claim, 5 Drawing Sheets(56)
